Filed July 15, 1968, Ser. No. 12,743

Term of patent 14 years

Int. Cl. D30—02

U.S. Cl. D30—13

FIG.1

FIG.2

FIG. 1 is a top perspective view of one of the individual feeder trays and a portion of the conveyor tube comprising a part of the mechanical feeder for caged poultry, embodying my new design;

FIG. 2 is a similar perspective view showing the individual trays grouped together with the conveyor tube, forming the design; and

FIG. 3 is a perspective view of the mechanical feeder for caged poultry in its completed stage, but showing same broken away for convenience of illustration.

The dominant features of my design are shown in full lines. The hidden end and side of the feeder tray in FIGURE 1 are the same as the end and side shown.

I claim:

The ornamental design for a mechanical feeder for caged poultry as shown and described.
